SAND MULLING APPARATUS FOR
FOUNDRIES

George Furman, Chicago, Ill., assignor to The
Beardsley & Piper Company, Chicago, Ill., a
corporation of Illinois

Application February 15, 1930. Serial No. 428,587

4 Claims. (Cl. 83—45)

The present invention relates generally to apparatus for mulling molding sand. More particularly the invention relates to that type of sand mulling apparatus which is adapted for use in a foundry or similar establishment and comprises a frame-structure, a member on the structure for supporting the sand, and a mulling unit which embodies one or more loosely mounted wheels or mullers and operates, during drive thereof, to swing or rotate the wheels bodily in a circular path over the sand supporting member for mulling purposes.

One object of the invention is to provide a mulling apparatus of the aforementioned type in which the member for supporting the sand is in the form of an endless belt which presents a smooth and even sand supporting surface and operates, during drive thereof, to feed the sand progressively into the path of the mullers and then to discharge the mulled sand into a hopper or onto the receiving end of a second conveyor.

Another object of the invention is to provide a sand mulling apparatus of the type under consideration in which the endless belt is formed of a resilient material such, for example, as rubber, and operates to support the sand yieldingly and in such a manner that an efficient mulling action is produced by the mullers without likelihood of the sand being pulverized or crushed to such an extent that its permeability is reduced to a point wherein it is unfit for use in connection with molds.

A further object of the invention is to provide a mulling apparatus in which the tread or peripheral part of the mullers as well as the endless belt is formed of rubber or a similar resilient material so that the sand is engaged frictionally as well as yieldingly and is mulled to the desired extent in a comparatively short period of time.

A still further object of the invention is to provide a sand mulling apparatus which is generally of new and improved construction and is an improvement upon previously designed apparatus for the same purpose by virtue of the fact that it permits of a continuous operation and operates to mull the sand efficiently and in an expeditious manner.

Additionally it is contemplated as one of the objects of the invention providing a mulling unit which embodies improved means for supporting and swinging the mullers.

Other objects of the invention and the various advantages and characteristics of the pres-

ent construction will be apparent from a consideration of the following detailed description.

The invention consists in the several novel features hereinafter set forth and more particularly defined by the claims at the conclusion hereof.

In the drawings which accompany and form a part of this specification or disclosure and in which like numerals of reference denote corresponding parts throughout the several views:

Figure 1 is a side elevational view of a mulling apparatus embodying the invention;

Figure 2 is a plan view;

Figure 3 is a vertical longitudinal section taken on the line 3—3 of Figure 2 and disclosing in detail the construction and arrangement of the endless belt for feeding the sand progressively to mullers;

Figure 4 is a vertical transverse section showing one of the mulling units and the drive mechanism therefor;

Figure 5 is a section taken on the line 5—5 of Figure 4;

Figure 6 is a horizontal section taken on the line 6—6 of Figure 4; and

Figure 7 is a horizontal section taken on the line 7—7 of Figure 4.

The apparatus which forms the subject matter of the invention is adapted primarily for use in a foundry and serves to mull, mix or recondition molding sand. It comprises an endless belt 8 which receives the sand that is to be mulled or mixed from a reservoir 9 and operates, during drive thereof, to carry the sand horizontally and in a rectilinear path past a pair of mulling units 10.

The endless belt 8 is mounted in an elongated metallic supporting frame 11 which is supported by means of blocks 12 on the floor of the foundry. The frame embodies a pair of channel iron beams 13 which form the sides of the said frame and consist of vertically extending webs 14, outwardly extending upper flanges 15 and outwardly extending lower flanges 16. The lower flanges rest upon and are suitably secured to the blocks 12. The frame, in addition to the channel iron side-forming beams 13, comprises cross members 17. The latter are formed of channel iron bars and have the ends thereof connected to the upper flanges 15 of the beams 13 by means of angle iron brackets 18. These brackets are welded or otherwise secured to the top faces of the flanges 15 and the contiguous parts of the cross members 17. An elongated substantially imperforate plate 19 rests upon and is sup-

ported by the cross members 17. This plate extends from one end of the supporting frame to the other and serves to support the upper reach of the belt 8.

5 The endless belt 8 is disposed between the beams 13 of the supporting frame. The receiving end of the belt extends around and is supported by a drum 20 which is mounted on a transversely extending shaft 21. The ends of 10 this shaft extend through elongated slots in the receiving ends of the beams 13 and are mounted in bearing blocks 22 which are slidably mounted in guideways 23 so that the drum 20 may be shifted in order to keep taut the belt 8. The 15 guideways 23 are secured to the outer faces of the webs of the channel iron beams 13 and are connected to the bearing blocks 22 by means of screws 24. By manipulating these screws the drum 20 may be shifted into the desired position. The discharge end of the endless belt 8 20 extends around and is supported by a drum 25 which is fixedly secured to a shaft 26. The ends of this shaft extend through the discharge ends of the beams 13 and are journaled in bearings 27 which are fixed to the outer faces of the webs 14. The lower reach of the belt is carried by a longitudinal series of rollers 28 which are located beneath the cross members 17 and the plate 19 and embody at the ends thereof 30 of pintles 29. These pintles extend through apertures in the webs 14 of the channel iron side-forming beams and are journaled in bearing brackets 30 which are positioned directly above the lower flanges 16.

35 The belt 8 is adapted to be continuously driven by means of an electric motor 31 so as to cause the sand to be carried from the reservoir 9 and fed progressively under the mulling units 10. The motor 31 is located at the discharge end 40 of the belt and is connected to drive reducing gearing which is mounted in a housing 32. The reducing gearing comprises a drive shaft 33 which is journaled in one end of the housing 32 and is connected by a coupling 34 to one end of the shaft 26 for the drum 25. When current is supplied to the motor 31 the rotor of the motor operates to drive the reducing gearing in the housing 32. This gearing in turn effects a low speed drive of the shaft 26 and causes a 45 continuous motion to be imparted to the belt. During drive of the belt the sand which, as hereinafter described, is supplied in regulated quantity from the reservoir 9, is precluded from being displaced laterally with respect to the side 50 margins of the upper reach of the belt by means of a pair of sheet metal trough-forming strips 35. The latter extend from one end of the supporting frame to the other and are secured to the side margins of the plate 19 by means of angle iron bars 36. These bars comprise vertically extending legs 36^a and horizontally extending legs 36^b. The vertically extending legs are riveted to the lower parts of the strips 35. The horizontally extending legs 36^b are welded 55 or otherwise secured to the top face of the plate 19. The strips 35 extend upwardly from the plate 19 and have their upper portions bent outwardly, as indicated in Figure 4, for trough-forming purposes. The angle iron bars 36 are 60 preferably arranged so that the strips 35 are located in close proximity to the side edges of the belt. The sand after being carried by the belt 8 past the mulling units is discharged onto a conveyor 37. The latter is arranged so that 65 the receiving end thereof is located beneath the

discharge end of the endless belt 8. A characteristic and an advantage of utilizing an endless belt in connection with the mulling apparatus and as the sand supporting medium is that the sand is subjected but once to the action of the mulling units 10 and therefore the likelihood of the sand being crushed or pulverized to too great an extent is eliminated. Another advantage is that the mulling operation may be carried out continuously in that the sand is fed progressively from the reservoir into the path of the mulling units and it is not necessary to stop the apparatus for sand loading and unloading purposes. Still another feature or advantage of utilizing an endless belt as the member for supporting the sand resides in the fact that a smooth and even surface is presented to the sand and as a result a thorough and uniform mulling action is obtained during operation of the apparatus.

90 The endless belt 8 is formed of rubber or a similar resilient material so that the sand is supported yieldingly. As a result of this arrangement excessive crushing of the sand is avoided and the mulling operation is expedited 95 for the reason that the sand is held frictionally as well as yieldingly. The mulling units 10 are positioned above the belt 8 and operate during drive of the belt to mull the sand so that it is 100 adapted for use in forming molds. One of the 105 units is located slightly inwardly of the receiving end of the belt and serves, during operation of the apparatus, to effect a preliminary mulling of the sand. The other unit is located between the 110 discharge end of the belt 8 and the first mentioned mulling unit and serves to complete the 115 mulling of the sand.

120 Each of the mulling units comprises a pair of wheels or mullers 38 which are loosely mounted on the ends of a horizontally extending axle 39. 115 This axle is carried by a spider 40 which is driven as hereinafter described, so as to swing the axle bodily and cause the mullers to travel in a circular path in order to effect the desired 125 mulling of the sand on the belt 8. The upper 130 central portion of the spider 40 is drivably connected by means of a key 41 to the lower end of a vertically extending driving sleeve 42. The latter is supported from above in a cast metal 135 housing structure 43. This housing structure 140 consists of a hollow cylindrically shaped member 44 and a pair of horizontally extending arms 45. The latter extend transversely with respect to the supporting frame for the belt 8 and are 145 supported above the plate 19 by means of a pair of brackets 46. These brackets are preferably formed of angle iron and embody legs 47, the lower ends of which are provided with horizontally extending lugs 48. The latter fit against the side margins of the plate 19 and are held 150 rigidly in place by bolts 49. The brackets 46, in addition to the legs 47, embody horizontally extending portions 50 which underlie the outer ends of the arms 45 and are secured to the latter by bolts 51. The housing structure 43 is 155 formed in two sections. These sections are provided with flanges 52 which extend outwardly from the cylindrical member 44 and are secured together by bolts 53 so that the housing structure is of a unitary character. The cylindrical 160 member 44 is joined to the arms 45 by vertically extending reinforcing webs 54 and comprises an annular side wall 44^a, a top wall 44^b, a bottom wall 44^c and an intermediate wall 44^d. The intermediate wall is formed integrally with the 165

central portion of the side wall 44^a and is located midway between the top wall 44^b and the bottom wall 44^c. The top wall 44^b forms a support for an electric motor 55 and is provided with a bearing 56 in which is journaled the rotor shaft 55^a of the motor. The interior of the cylindrical member 44 forms a compartment 57 in which is disposed planetary or epicyclic gearing for driving the spider 40. The gearing is driven by the motor 55 and comprises a pinion 58 which is keyed to the rotor shaft 55^a of the motor; a plurality of gears 59 which are driven by the pinion 58, mesh with an internal gear 60 on the inner periphery of the side wall 44^a of the member 44 and are connected to a vertically extending tubular element 61 by means of studs 62; a pinion 63 which is keyed or otherwise secured to the central portion of the element 61; and a plurality of gears 64 which are driven by the pinion 63, mesh with an internal gear 65 on the inner periphery of the side wall 44^a and are connected to a flanged portion 42^a on the upper end of the driving sleeve 42 by means of studs 66. The tubular element 61 is loosely mounted in the sleeve 42 and is provided at its upper end with a radially extending flange 61^a which rests upon the intermediate wall 44^d and has sockets for receiving the studs 62. The driving sleeve 42 extends through a bearing member 67 which is formed integrally with the bottom wall 44^c of the member 44 and supports the flanged portion 42^a so that the sleeve is supported against downward displacement. The lower end of the driving sleeve is provided with a nut 68 which supports the spider 40. When the motor 55 is actuated, the planetary or epicyclic gearing in the chamber 57 rotates the driving sleeve 42. The latter in turn swings the spider 40 and the axle 39 so as to cause the mullers 38 to move in a circular path and effect the desired mulling or mixing of the sand on the subjacent portion of the belt 8. The axle 39 is provided with a pair of collars 69. The latter are movable vertically in elongated slots 70 in the spider so that the axle 39 is movable vertically and permits the mullers to raise and lower in response to variations in the thickness of the layer of sand on the conveyor. The collars 69 are supported by a pair of adjusting screws 71 so that the shaft 39 is sustained in a position wherein the mullers 38 are out of contact with the conveyor. The screws 71 extend through the lower part of the spider 40 and are adapted to be locked in place against rotation by lock nuts 72. By adjusting the screws 71, the mullers 38 may be raised or lowered into the desired position with respect to the endless belt on which the sand is supported. The mullers are mounted in bronze bushings 73 which surround the outer ends of the shaft 39 and are positioned between the collars 69 and a pair of retaining devices 74. The latter are connected to the ends of the shaft 39 and are disposed in cup-shaped housings 75 so that sand is excluded therefrom. The mullers 38 are provided with tires 38^a. These tires are formed of hard rubber and are cemented or otherwise secured to the peripheries of the mullers. A characteristic and an advantage of utilizing rubber tires on the mullers is that the sand which is yieldingly supported by the belt is yieldingly engaged by the mullers and as a result is mulled quickly and without damage of being pulverized to too great an extent. In practice it has been found that tires which are substantially equal in density to solid rubber vehicle tires accomplish expeditiously the desired mulling of the sand in connection with the belt and will wear substantially as well as steel rims or all-metal muller wheels. By utilizing coating rubber mulling surfaces the sand is subjected to a substantially uniform pressure and is mulled uniformly and evenly. By precluding the possibility of excessive crushing or pulverizing the mulled sand when rammed into a flask to form a mold has the necessary permeability to permit of the escape of gases emanating from the molten metal during the pouring operation. In view of the fact that the sand is fed by the belt during operation of the mulling units and the coating mulling surfaces are formed of rubber, the sand is efficiently and quickly mulled to the desired extent.

To turn the sand over and direct it into the path of the mullers during operation of the units 10, rakes 40^a are provided. These rakes are adjustably mounted on horizontally extending arms 40^b which project outwardly from the spiders 40 and are arranged at right angles to the axles 39.

The reservoir 9 operates to store the sand that is to be mulled and operates, as hereinafter described, to supply the sand in regulated quantity to the receiving end of the belt 8. It is preferably elongated as indicated in Figures 1, 2 and 3, and is supported upon a framework 76 which is located in front of the receiving end of the conveyor supporting frame. The framework 76 comprises a pair of channel iron sills 77 which are arranged in parallel relation and are supported by means of standards 78. The latter are mounted on and project upwardly from a base 79 which rests upon the floor of the foundry. The sides of the reservoir are fixed to the sills 77 by means of angle iron bars 80 which are bolted or otherwise secured to the top flanges of the sills. The top of the reservoir is open so that it can be filled from an overhead sand delivery system or in any other suitable manner. The bottom of the reservoir is formed by an endless conveyor 81 which is adapted to feed the sand forwardly through a discharge opening 82 in the front wall of the reservoir. This conveyor consists of an endless series of slats 83. The latter are shaped so that they overlay one another and are connected to a pair of endless chains 84 by means of pivot lugs 85. The rear ends of the chains extend around a pair of sprocket wheels 86 which are mounted on a transversely extending shaft 87. The ends of this shaft extend through elongated slots 88 in the rear ends of the sills 77 and are journaled in bearing blocks 89 which are slidably mounted in guideways 90. The latter are secured to the sills 77 and are connected to the bearing blocks 89 by means of screws 91. When it is desired to tighten the conveyor 81, the screws 91 are adjusted so as to shift the bearing blocks 89 and the shaft 87. The front ends of the chains 84 extend around a pair of driving sprockets 92 which are mounted on a transversely extending shaft 93. The latter is located beneath the discharge opening 82 and is arranged so that the ends thereof project through the front ends of the channel iron sills 77. The conveyor 81 is operated to feed the sand step by step through the discharge opening 82 by means of driving mechanism which consists of a motor (not shown) in a housing 94. The driving mechanism, in addition to the motor, comprises an eccentric 95 which projects from one side of the housing 94; a pawl 96

which is mounted on and operated by the eccentric; and a ratchet wheel 97 which is fixed to one end of the shaft 93 and is driven by the pawl. The housing 94 is supported on the base 5 79 and is disposed beneath the central portion of the conveyor 81. When the conveyor is driven by the mechanism heretofore described, the sand is fed through the discharge opening 82. From said discharge opening 82, the sand passes 10 onto a chute 98. The latter is connected to the front ends of the sills 77 and is adapted to direct the sand onto the receiving end of the endless belt 8.

The discharge of sand through the opening 15 82 is controlled by means of a gate 99 which is vertically movable and is in the nature of a valve whereby the height of the discharge opening may be varied to regulate the quantity of sand that is discharged from the reservoir. The 20 gate is supported by a pair of arms 100 which project rearwardly and are pivoted to the sides of the reservoir so that the gate can swing upwardly or downwardly. The arms are preferably arranged so that the gate will be shifted upwardly when engaged by scrap in the sand in order to permit such scrap to pass thereunder and move out of a position wherein it would tend to obstruct the discharge opening and interfere with the regulated delivery of the sand. The 25 raising and lowering of the gate is effected by means of mechanism which comprises a transversely extending shaft 101, a drum 102 on the shaft and a cable 103. The latter is wound around the drum and is connected at its distal end to the gate 99. The shaft 101 is adapted to be turned for drum rotating purposes by means of a hand wheel 104. When the hand wheel is turned in one direction, the drum 102 is rotated so as to cause the cable to wind thereon and raise the gate 99. When the hand wheel 104 is turned in the opposite direction, a lowering of the gate is effected. The gate 99 and the conveyor 81 exemplify means for supplying sand in regulated quantity to the receiving end of 30 the endless belt 8. By providing sand supply means of the character herein described, the sand is caused to be distributed evenly over the belt 8 and is in the nature of a layer which is substantially of uniform thickness throughout, 35 40 45

50 Assuming that the various motors are running, the operation of the mulling apparatus is as follows:

The endless conveyor 81 is moved step by step by means of the pawl and ratchet and causes the 55 sand in the reservoir 9 to be fed onto the chute 98. The gate 99 controls the discharge of the sand through the opening 82 so that the feeding of the sand is uniform and the sand is caused to be delivered onto the belt 8 in the form of a 60 layer of uniform thickness. Said belt operates to convey the sand from the chute 98 towards the discharge end of the supporting frame. As the sand is moved on the belt 8 under the mullers 38, the desired mulling takes place. By virtue 65 of the fact that the tires and the belt engage the sand yieldingly and frictionally the mulling is done expeditiously and without likelihood of excessive pulverizing or crushing. After the sand has been subjected to the action of the 70 mulling units it is discharged from the belt 8 and is in readiness for use in connection with molding. The mullers 38 are preferably supported so that they are positioned a slight distance above the endless belt 8. By supporting the mullers 75 in this manner, wear of the tires and the belt

is avoided. In the event that it should be desired to change the position of the mullers with respect to the belt 8, it is only necessary to adjust the screws 71. During operation of the apparatus, the discharge of the sand from the 80 reservoir 9 is controlled by the gate 99. If it is desired to feed the sand to the endless belt 8 so that it is in the form of a relatively thick layer, the gate 99 is raised so as to increase the discharge opening. If it is desired to deliver the 85 sand to the belt 8 in comparatively small quantities, the gate 99 is lowered so as to decrease the size of the discharge opening 82. In the event that the gate encounters scrap in the sand it is automatically forced upwardly so as to permit such scrap to pass thereunder.

The mulling apparatus herein disclosed is exceedingly efficient in operation in view of the fact that the endless belt permits of a continuous operation and serves to move the sand progressively into and out of the path of travel of the mullers. Since the belt is formed of rubber it presents a smooth and even supporting surface for the sand and is sufficiently yielding to prevent the possibility of the sand being crushed 100 to too great an extent.

The invention is not to be understood as restricted to the details set forth, since these may be modified within the scope of the appended claims, without departing from the spirit and 105 scope of the invention.

Having thus described the invention, what I claim as new and desire to secure by Letters Patent, is:

1. In a mulling apparatus of the character 110 described, the combination of supporting means, an endless belt for supporting the material to be mulled, carried by the supporting means and formed of elastic material so as to support the material yieldingly, a muller positioned above 115 the belt and adapted to operate on the material, and means for driving said belt so as to feed the material progressively under the muller for mulling purposes.

2. In a mulling apparatus of the character 120 described, the combination of a frame, an endless rubber belt carried by said frame and operative to support the material to be mulled, a power driven mulling unit comprising a muller positioned above the belt and movable bodily in a 125 circular path over the material for mulling purposes, and means for driving the belt so as to feed the material progressively into the path of travel of the material.

3. In a mulling apparatus of the character 130 described, the combination of a frame, an endless rubber belt carried by said frame and adapted to support the material to be mulled, a power-driven mulling unit comprising a muller wheel positioned above the belt and movable bodily in 135 a circular path over the material, said muller wheel being provided with a rubber tire and adapted, during operation of the unit, to engage the material yieldingly and coact with the belt to effect a mulling of the material, and means for 140 driving the belt so as to feed the material progressively into the path of travel of the muller wheel.

4. In an apparatus of the character described, the combination of an elongated frame consisting of a pair of laterally spaced sides, a substantially flat member supported on the frame between the sides so that it is movable lengthwise of the frame in a substantially rectilinear path, a power-driven mulling unit supported on the 145

150

frame-sides comprising a muller wheel positioned above the member and movable bodily in a circular path over the material for mulling purposes, said muller wheel being provided with a solid rubber tread of such thickness and character that the material is engaged yieldingly and is held frictionally against slippage, and means for

moving the member rectilinearly so as to feed the material progressively into the path of travel of the wheel and effect, during moving of the wheel, an efficient and ready mulling of the material by the combined movements of the muller and the wheel. 80
